[57] CLAIM

The ornamental design for a vehicle body, as shown and described.

DESCRIPTION

FIG. 1 is a front perspective view illustrating a vehicle body constructed in accordance with the teachings of the present invention.

FIG. 2 is a side view, it will be understood that the side opposite to that shown is a substantial mirror image thereof.

FIG. 3 is a rear perspective view thereof.

FIG. 4 is a front view thereof; and,

FIG. 5 is a rear view thereof.

It will be understood that the broken line showing of the wheels and tires throughout the drawings is for illustrative purposes only and forms no part of the subject invention.
